TIRE

Charles C. Custer, Akron, Ohio, assignor to The B. F.
Goodrich Company, New York, N.Y., a corporation
of New York

Filed Mar. 2, 1966, Ser. No. 1,261

Term of patent 14 years

(Cl. D90—20)

Fig. 1

FIG. 2

FIG. 3

FIG. 1 is a perspective view of a tire showing my new design, it being understood that the tread and sidewall portion shown are repeated throughout the circumference of the tire and that the opposite side is identical to the side shown;

FIG. 2 is an enlarged fragmentary top plan view of the portion of the tire shown in FIG. 1; and

FIG. 3 is a fragmentary transverse sectional view through the tire substantially on the plane indicated by the line 3—3 of FIG. 2.

The dominant features of my design reside in those portions shown in full lines.

I claim:

The ornamental design for a tire, substantially as shown and described.
